T. J. STURTEVANT.
AIR SEPARATOR.
APPLICATION FILED FEB. 16, 1920.

1,379,730.

Patented May 31, 1921.

UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

AIR-SEPARATOR.

1,379,730.

Specification of Letters Patent.

Patented May 31, 1921.

Application filed February 16, 1920. Serial No. 358,984.

To all whom it may concern:

Be it known that I, THOMAS J. STURTEVANT, a citizen of the United States, residing at Wellesley, in the county of Norfolk and 5 State of Massachusetts, have invented an Improvement in Air-Separators, of which the following description, in connection with the accompanying drawings, is a specification, like characters on the drawings representing like parts.

The invention to be hereinafter described relates to air separators for grading materials. Separators of this general type have a separating chamber in communication with 10 a collecting chamber. A fan causes an air current to move upward through the separating chamber and into the collecting chamber. The materials to be graded are introduced into the path of the rising air current, 15 and the heavier particles or tailings gravitate downward through the rising air current, while the lighter particles or fines are carried along by the air current into the collecting chamber. The separating chamber 20 and the collecting chamber are provided with outlets through which the tailings and 25 the fines may be delivered respectively.

One of the purposes of the present invention is to provide a simple and efficient separator construction whereby the rising air current may be caused to whirl upward in a spiral path, the location of the fan being such that the air current may pass a substantial distance above the fan before leaving 30 the casing of the separator, in order that the fines may have ample time to gravitate downward through the air current in the collecting chamber and thereby desirably clean the air of the particles before the air 35 current leaves the collecting chamber.

Another purpose of the invention is to provide a by-pass or passage for conducting the air current from the collecting chamber back to the separating chamber, so that the 40 air current may pass in a closed circuit 45 through the separating chamber, the collecting chamber and the by-pass or passage, said air current being produced by the fan which may be located in the opening between 50 the separating and collecting chambers.

Another purpose of the invention is to provide guiding means, in the present instance, in the form of a conical casing intermediate the fan and the top of the separator to coöperate with the casing of the col-

lecting chamber and contribute to the guidance of the air current from the opening between the chambers to the mouth of the bypass or passage for conducting the air current from the collecting chamber back to the 60 separating chamber.

With the aforesaid and other purposes in view, the character of the invention may be best understood by reference to the following description of one good form of the invention shown in the accompanying drawing, wherein the separator is shown in vertical section.

Referring to the drawing, the separator shown therein comprises a casing 1 having 70 a lower conical wall 3 and an upper conical wall 5 meeting and secured together by bolts 7 and diverging from their juncture for a purpose to be described. The lower conical wall 3 tapers downward to a discharge outlet 75 9 for the fines, and the upper conical wall 5 tapers upwardly and is provided with a head 11. The casing may be supported by feet 13 adapted to rest on beams or other appropriate means.

Mounted within the outer casing described, is an inner casing 15, in the present instance, comprising a lower conical wall 17 and an upper conical wall 19 meeting and secured together, and diverging from their juncture for a purpose to be described. The inner wall may be supported by brackets 21 interposed between the upper conical wall 3 and the lower conical wall 17 and conveniently opposite the casing supporting brackets 13. The inner casing 15 divides the outer casing into a separating chamber 23 and a collecting chamber 25.

Suitable means may be provided to introduce the materials to be graded into the 95 separator. To accomplish this, in the present instance, a hopper 27 may be provided communicating with a feed tube 29 depending from said hopper a substantial distance into the separating chamber.

Suitable means may be provided to receive the materials from the feed tube and to distribute the same into the separating chamber. This means, in the present instance, comprises a rotary table or disk 31 105 having a hub 33 mounted on the upper end of a vertical shaft 35 journaled in an upper bearing 37 and a step bearing 39 carried by a casing 41. Fast on the vertical shaft 35 is a bevel gear 43 meshing with and driven 110

by a bevel gear 45 fast on a horizontal shaft 47 journaled in bearings in a tube 49 projecting from the casing 41 through the inner casing wall 17 and the outer casing wall 3. 5 The tube 49 may have wide flanges 51 and 53 secured to said walls, the construction being such that the tube 49 may be readily inserted into its operative position or removed therefrom, thereby facilitating access to the bevel 10 gears for the purpose of substituting new ones therefor when desired. At the outer end of the horizontal shaft 47 is a pulley 55 which may be driven by a belt from any suitable source of power.

15 The construction is such that materials falling through the feed tube 29 onto the rotary table 31 will be thrown outward thereby into the separating chamber under the influence of centrifugal force, and will 20 be distributed into the path of the air current rising in the separating chamber, as more fully hereinafter described.

To cause the air current to move upward through the separating chamber, a fan 57 25 may be provided comprising vanes 59 secured to a hub 61 mounted on a short sleeve 63 projecting upward from a cone 65 encircling the feed tube 29. The cone 65 has a flange 67 at the lower end thereof mounted 30 on a ring 69 above the distributor table 31 and secured thereto by bolts 71, said ring 69 being spaced above said table by sleeves 73 on said bolts. Thus, the fan 57 is supported 35 by the distributor table 31 through the intermediary of the cone 65, and is rotated by the same transmission which serves to rotate said table.

The fan may be located above the ring 40 plate 75 secured to and projecting outward from the upper edge of the conical wall 19 of the inner casing.

To contribute to the guidance of the air current and fines whirled by the fan outwardly from the separating chamber into 45 the collecting chamber, a cone casing 77 may be provided having a base 79 above the fan and with a diameter desirably substantially the same as the diameter of the ring plate 75 referred to. This cone casing may be 50 conveniently secured to and supported by the feed tube 29 which projects downward therethrough. This cone casing 77 may co-operate with the upper conical wall 5 of the outer casing, and contribute to the guidance of the 55 air current upward toward the head 11 of the outer casing, and tend to prevent eddy currents of the air as it whirls upwardly.

Suitable means may be provided to conduct the air current from the collecting 60 chamber back to the lower end of the separating chamber. This means, in the present instance, comprises a throat 80 encircling the feed tube 29 and projecting through the head of the outer casing. A pipe 81 leads from 65 this throat laterally outward and thence

downward along the outer casing and communicates with a pipe 83 projecting obliquely upwardly through the lower conical wall 3 of the outer casing, the upper end of said pipe 83 being connected to and communicating with the lower conical wall 17 of the inner casing. The air current on leaving the collecting chamber will pass through the pipes 81 and 83 and return to the separating chamber. To control the air current passing 70 through the pipe 81, a valve 85 may be mounted therein and have a handle 87 to facilitate adjustment of the valve to vary the draft through the pipe 81 as desired. 75

The air current rising upwardly through 80 the separating chamber will pass along the lower conical wall 17 of the inner casing, and thence along the upper conical wall 19 of said casing, and substantially at the junction of said walls will receive the materials 85 thrown outward by centrifugal force by the rotary distributor table 31. The heavier particles or tailings will gravitate downward along the lower conical wall 17 and pass through the inclined pipe 83. To discharge the tailings therefrom, an outlet 89 90 may be provided at the lower end of the inclined pipe 83, and may have a valve or gate 91 pivotally mounted on a bracket 93 and urged to closed position by a weight 95 95 on an arm 97 connected to said valve. When a sufficient weight of tailings has accumulated on the valve 91, it will overcome the weight 95 and open said valve, and allow discharge of the tailings through the outlet 100 89. Thereupon, the weight 95 will serve automatically to return the valve to closed position.

The centrifugal effect of the rotary distributor on the materials, and the whirling 105 effect on the air produced by the fan will tend to cause the materials to be thrown outwardly toward the upper conical wall 19 of the separating chamber, and the materials will be thrown outward different distances 110 depending on their relative weights or other characteristics thereof. This will tend to prevent the tailings from impinging upon and pulling the fines downward through the separating chamber, and thereby contribute to the efficient separation of the materials. The fines will move upward with the rising air current, and be whirled by the fan outwardly between the ring plate 75 and the cone casing base 79 into the collecting chamber. The centrifugal effect of the whirling air current will tend to throw the fines against the upper conical wall 5 of the outer casing, and they will be deflected downward thereby, and flow thence 115 along the lower conical wall 3 of the outer casing, and be discharged through the fines outlet 9. The air current will whirl in a long spiral path upward from the fan to the throat 80, and pass thence through the pipes 120 125 130

81 and 83 and return to the separating chamber. Thus, the air will pass in a closed circuit upward through the separating chamber outward past the fan into the collecting 5 chamber, and thence upward and through the pipes in a closed circuit.

The separator described is simple in construction, and serves efficiently to separate the materials to be graded introduced into 10 the separator.

It will be understood that the invention is not limited to the specific embodiment shown, and that various deviations may be made therefrom without departing from the 15 spirit and scope of the appended claims.

What is claimed is:—

1. An air separator for grading materials, comprising, in combination, an outer casing, an inner casing therein dividing the same 20 into a separating chamber and a collecting chamber, said inner casing positioned a substantial distance from the upper end of the outer casing, a hopper at the top of the casing, a feed tube extending from the hopper 25 down to the separating chamber, a member supported by said tube in spaced relation to the upper end of the separating chamber and coöperating with the upper end of said chamber to form a restricted fan receiving 30 space, a fan rotatable in said restricted space to cause an air current to circulate upward through the separating chamber into the collecting chamber, and a conduit for conducting air from the upper end of the collecting 35 chamber to the lower end of the separating chamber and in an upward direction through said lower end.

2. An air separator for grading materials, comprising, in combination, an outer casing, 40 an inner casing therein dividing the same into a separating chamber and a collecting chamber, a by-pass pipe leading from the upper end of the collecting chamber to the lower end of the separating chamber, a fan 45 above the separating chamber for causing an air current to circulate through the separating chamber, collecting chamber and by-pass pipe in a closed circuit, a feed tube projecting from the top of the outer casing 50 downward into the separating chamber to deliver materials to be graded therein, and means intermediate the top of the outer casing and the fan to contribute to the guidance of the air from the collecting chamber 55 to the by-pass pipe, said separating chamber being constructed to direct the tailings into the by-pass pipe.

3. An air separator for grading materials, comprising, in combination, an outer casing 60 comprising upper and lower conical walls meeting and diverging from their juncture, an inner casing comprising upper and lower conical walls meeting and diverging from their juncture and dividing the outer casing 65 into a separating chamber and a collecting

chamber, a by-pass pipe leading from the upper end of the collecting chamber to the lower end of the separating chamber, a conical member mounted in the collecting chamber above the separating chamber and 70 spaced therefrom, a fan located intermediate said conical member and said separating chamber for causing an air current to circulate through the separating chamber, collecting chamber and by-pass pipe in a closed 75 circuit, and means to rotate said fan.

4. An air separator for grading materials, comprising, in combination, an outer casing having an opening in the top thereof, an inner casing dividing the outer casing into 80 a separating chamber and a collecting chamber, a by-pass pipe projecting from said opening to the lower end of the separating chamber, a feed tube smaller than said opening and projecting downward therethrough 85 toward the separating chamber for introducing materials to be graded therein, a fan for causing an air current to circulate through said separating chamber, collecting chamber and by-pass pipe in a closed circuit, said separating chamber constructed 90 to direct the coarser materials into said pipe to expose the materials to the air current rising therein, and an outlet in said pipe for discharging the coarser materials. 95

5. An air separator for grading materials, comprising, in combination, an outer casing, an inner casing therein dividing the same into a separating chamber and a collecting chamber, a feed tube projecting through the 100 top of the outer casing downward into the separating chamber, a rotary distributer in said separating chamber to receive materials from said feed tube, a conical member carried by said rotary distributer and encircling 105 said feed tube, a fan mounted on said conical member, a vertical shaft for said rotary distributer, a horizontal shaft, and bevel gears on said shafts for imparting rotation 110 from said horizontal shaft to said vertical shaft.

6. An air separator for grading materials, comprising in combination, a collecting casing, a separating casing therein having a downwardly converging lower end, a pipe 115 extending downward from said converging end to conduct tailings from the separating casing, a tailing outlet in said pipe, a feeding tube projecting from the top of the collecting casing toward the separating casing, 120 a distributer within the separating casing to receive materials from the feeding tube, a shaft for driving the distributer, means for producing an air current rising through the separating casing into the collecting casing, and a by-pass conduit leading from the upper end of the collecting casing to the lower portion of said pipe to conduct an air current upwardly through the tailings in 125 said pipe and the separating casing. 130

7. An air separator for grading materials, comprising, in combination, an outer casing having a fines outlet at the lower end thereof and an air outlet at the upper end thereof,
- 5 an inner casing in said outer casing dividing the same into a separating chamber and a collecting chamber, said separating chamber having an upper end communicating with the collecting chamber and an outlet at the
- 10 lower end thereof, a pipe leading from the air outlet of the outer casing to the outlet at the lower end of the separating chamber, a tailings outlet in said pipe, means to cause an air current to circulate through the sep-

arating chamber, collecting chamber and bypass pipe in a closed circuit, means in the upper part of the collecting chamber for deflecting the air current outward and upward, means to feed the materials to be graded downward into said separating chamber, a rotary distributer for receiving the materials and whirling the same outward into the path of the air current moving upward in the separating chamber, and driving means for said rotary distributer. 15
